UNITED STATES PATENT OFFICE.

PAULINE JANDOS, OF CHICAGO, ILLINOIS.

MEDICAL INSTRUMENT.

1,273,066.

Specification of Letters Patent. Patented July 16, 1918.

Application filed February 23, 1918. Serial No. 218,776.

To all whom it may concern:

Be it known that I, PAULINE JANDOS, a citizen of the United States, residing at Chicago, in the county of Cook and State 5 of Illinois, have invented new and useful Improvements in Medical Instruments, of which the following is a specification.

This invention relates to a medical instrument or appliance.

10 The object of the invention is to produce a simple appliance, in the nature of a cup shaped member designed to be placed against a congested part of the patient to create a vacuum therearound and draw the skin 15 and portion of the flesh surrounding the congested part into the cup, and thus relieve the congestion.

A further object of the invention is to produce a medical appliance in the nature 20 of a suction member in which a flame is employed in burning oxygen to create a vacuum, and wherein a determined quantity of air may be admitted into the device to reduce the vacuum to accord with the degree 25 of suction by the device upon the part of the person acted on thereby, as well as to entirely destroy the vacuum to permit of the removal of the device from the patient.

Other objects and advantages will appear 30 as the nature of the invention is better understood, reference being had to the accompanying drawings, in which,

Figure 1 is a view illustrating the application of the improvement.

35 Fig. 2 is an approximately central longitudinal sectional view, upon a greatly enlarged scale through the improvement.

Fig. 3 is a top plan view of the same.

Fig. 4 is a bottom plan view of the same.

40 Fig. 5 is a sectional view through a modification.

As disclosed by the drawings the improved appliance is in the nature of a cup member 6 which is pear-shaped in plan and 45 which has its edge provided with an out-turned bead 7.

In the preferred embodiment of the improvement the cup 6, at the center thereof is provided with an opening surrounded by an 50 annular flange or boss 8, the said boss having internal threads which are designed to be engaged by external threads on a valve or stopper 9. The head of the stopper 9 is provided with a substantially rectangular 55 slot 10, and through this slot may be passed a belt 11, having a buckle at one of the ends

thereof to engage with the other end, whereby the device may be strapped on the person of the patient, as illustrated in Fig. 1 of the drawings.

60 Integrally formed in the cup is an angle member providing a bracket 13, the horizontal arm of the said bracket having, upon its outer face an annular flange 14 which is disposed directly central of the opening in the cup and which provides a socket having a short candle 15. The candle is, of course, ignited and the valve or stopper screwed on the cup. The device is then applied to the congested part of the patient, and as the 70 flame consumes the oxygen a vacuum will be created which will cause a suction upon the part of the flesh to which the device is applied, drawing the said part into the cup. The device is preferably constructed of some 75 suitable transparent material, glass preferred, and when the vacuum is created, and the flame from the candle extinguished the valve or stopper 9 may be regulated to permit of a slight entrance of air into the cup, 80 so as to reduce the vacuum and regulate the suction. When the stopper is wholly removed the air flowing into the cup destroys the vacuum and permits of the removal of 85 the device from the patient.

85 In Fig. 5 the construction is substantially similar to that described, except that the cup 15 is provided with a restricted opening or perforation 16 arranged directly above the candle 17. With this construction adhesive paper or the like may be applied to the outer surface of the cup to close the opening 16, and by perforating or destroying this paper air will be admitted through the perforation 16 and destroy the vacuum 95 therein, and permit of the removal of the device from the patient. The pear shape of the cup allows the same to be readily arranged between the breasts of the user, the apex of the cup being thus properly positioned at the lower end of the sternum directly over the solar plexus, at which part of the human body there is an important group of nerve centers.

100 It is believed, from the above description, when taken in connection with the drawings that the simplicity and advantages of the construction will be apparent without further detailed description.

110 Having thus described the invention, what I claim is:

1. In a medical appliance, for the pur-

pose set forth, a cup having a central opening therein, a stopper constituting a valve normally closing said opening, said stopper having its head portion provided with a slot 5 to receive a suspending element, and a bracket in the cup designed to receive thereon an ignitable element.

2. In a medical appliance, for the purpose set forth, a transparent cup member 10 having a central opening therein, a valve

controlling said opening, said valve having a slot at the outer portion thereof to receive a suspending element, an angle bracket integrally formed with the cup and arranged interiorly thereof, and said bracket having 15 its horizontal arm formed with an annular flange designed to receive an ignitable element.

In testimony whereof I affix my signature.
PAULINE JANDOS.
